UNITED STATES PATENT OFFICE.

MARTHA HARRIS, OF DENVER, COLORADO.

DESIGN FOR AN IMITATION-HEMMED PAPER NAPKIN.

48,720.

Specification for Design.

Patented Mar. 14, 1916.

Application filed August 27, 1915. Serial No. 47,708. Term of patent 14 years.

To all whom it may concern:

Be it known that I, MARTHA HARRIS, a citizen of the United States, residing in the city and county of Denver and State of Colorado, have invented a new, original, and ornamental Design for Imitation-Hemmed Paper Napkins, of which the following is a specification, reference being had to the accompanying drawing.

In this drawing the figure is a top plan view of a paper napkin showing my new design.

I claim:

The ornamental design for an imitation hemmed paper napkin, as shown.

In testimony whereof I affix my signature in presence of two witnesses.

MARTHA HARRIS.
